UNITED STATES PATENT OFFICE

172,996

TIRE

Maineard L. Smith, Akron, Ohio, assignor to The Goodyear Tire & Rubber Company, Akron, Ohio, a corporation of Ohio

Application January 15, 1954, Serial No. 28,540

Term of patent 14 years

(Cl. D90—20)

To all whom it may concern:

Be it known that I, Maineard L. Smith, a citizen of the United States, residing at 2912 Sanitarium Road, Akron, in the county of Summit and State of Ohio, have invented a new, original, and ornamental Design for a Tire, of which the following is a specification, reference being had to the accompanying drawing, forming part thereof.

Fig. 1 is a perspective view of a tire, showing my new design; and

Fig. 2 is a cross-sectional view taken on the line 2—2 of Fig. 1.

I claim:

The ornamental design for a tire, as shown.
